(57) **CLAIM**

The ornamental design for a wheel for a stroller, as shown and described.

DESCRIPTION

FIG. 1 is a perspective view of a wheel for a stroller;

FIG. 2 is a left side elevation view thereof;

FIG. 3 is another perspective view of the wheel for a stroller;

FIG. 4 is a right side elevation view thereof; and,

FIG. 5 is a left side elevation view thereof.

The broken lines in the drawings, which illustrate environmental structure or boundaries of the wheel for a stroller, do not form a part of the claimed design.
